DESIGN FOR A RUG

William F. McCabe, New York, N. Y., assignor to
Bigelow Sanford Carpet Co., Inc., a corpora-
tion of Massachusetts

Application October 25, 1933. Serial No. 49,554

Term of patent 7 years

To all whom it may concern:

Be it known that I, WILLIAM F. McCABE, a citizen of the United States, residing at New York city, in New York County and State of New York, have invented a new, original, and ornamental Design for a Rug, of which the following is a specification, reference being had to the accompanying drawing forming part thereof.

The figure of the drawing is a face view of

the quarter section of my design. The intersection of the dot and dash lines indicating the center point of the design. The unit of the design reverses at the center points as shown by the extensions beyond the centers.

I claim

The ornamental design for a rug, substantially as shown and described.

WILLIAM F. McCABE.
